UNITED STATES PATENT OFFICE.

LAWSON L. JAFFE, OF CHICAGO, ILLINOIS, ASSIGNOR TO M. S. LEVINSON & COMPANY,
OF CHICAGO, ILLINOIS, A CORPORATION OF ILLINOIS.

DESIGN FOR A RING OR SIMILAR ARTICLE.

Application filed May 26, 1924. Serial No. 9,711. Term of patent 7 years.

To all whom it may concern:

Be it known that I, LAWSON L. JAFFE, a citizen of the United States, residing at Chicago, in the county of Cook and State of Illinois, have invented a new, original, and ornamental Design for Ring or Similar Article, of which the following is a specification, reference being made to the drawing forming a part thereof.

In the annexed drawing Fig. 1 is a perspective view and Fig. 2 is a face view of my new ring.

I claim:

The ornamental design for a ring or similar article as shown.

LAWSON L. JAFFE.
